COSTUMER

Rollo Burkett Curtiss, Richland, N. Y.

Application November 23, 1936, Serial No. 112,411

3 Claims. (Cl. 211—178)

The invention appertains to supports, and more particularly, to clothes racks known as costumers.

The primary object of the invention is to provide an extensible costumer which, when extended, affords accommodation for a considerably greater number of garments than the ordinary costumer, and which may be collapsed to assume the general form and appearance of the ordinary costumer which usually comprises a single post or standard.

A further object of the invention is to provide an extensible and collapsible costumer of particularly simple, sturdy and inexpensive construction.

Another object of the invention is to provide in an extensible costumer, improved bracing means which, when extended, rigidly brace the complementary sections of the costumer against accidental collapsing, at least one of said bracing means being adapted to support a relatively large number of so-called garment hangers or the like, at an elevation above the floor which insures against contact of the garments with the floor when suspended from the support, and having sufficient strength to bear the weight of heavy garments such as overcoats, topcoats, etc.

A still further object of the invention is to provide an improved folding brace, characterized by its adaptation to assume a rigid or locked condition automatically when fully extended, and which may be released or "broken" in a very simple manner and with a minimum expenditure of effort, so that it may be conveniently folded or collapsed.

Still another object of the invention is to provide an improved base or foot assembly of the "knocked-down" type, whereby the costumer may be packaged so as to occupy a minimum space, which is an important feature from a shipping standpoint.

Other and further objects and advantages of the invention will be hereinafter described, and the novel features thereof defined by the appended claims.

In the drawings:—

Figure 1 is a perspective view of a costumer constructed according to my invention, the costumer being shown in its collapsed or folded condition;

Figure 2 is a perspective view of the costumer in its extended position;

Figure 3 is an enlarged fragmentary detail view, in side elevation, of the upper bracing means which constitutes a support adapted to sustain a relatively large number of garment hangers from which the garments may be suspended, the

dotted lines illustrating the brace in its fully extended, locked position, and the full lines illustrating the brace in a "broken" or partially folded position;

Figure 4 is a sectional view, taken approximately on the line 4—4 of Figure 3;

Figure 5 is a plan view of the brace in its fully extended condition, as viewed from the underside thereof;

Figure 6 is an enlarged fragmentary detail view, partly in section, illustrating the construction and pivotal connection of an end of the upper brace with one of the halves of the costumer standard;

Figure 7 is a horizontal sectional view through the costumer standard in its collapsed position, and particularly illustrating the instrumentalities for releasably holding the costumer in its collapsed condition;

Figure 8 is an elevation of the lower portion of one of the complementary halves of the costumer, and particularly illustrating my improved base assembly as viewed from the inward side thereof; and

Figure 9 is a view generally similar to Figure 6, and illustrating a somewhat modified form of brace end and standard construction for maintaining the complementary standard sections in parallel relation when the brace arms are fully extended.

Like reference characters designate corresponding parts in the several figures of the drawings.

Referring first to Figures 1 and 2, I have shown my costumer as embodying a pair of upright complementary standard sections or halves, respectively designated 1 and 2. The lower end of each standard section is provided with feet, generally designated 1' and 2', and adjacent to the upper ends of the standard sections are mounted a plurality of hooks, designated 3, upon which garments may be hung in the usual manner.

The inner faces of the standard sections 1 and 2 are each provided with upper and lower longitudinal grooves 4, 4' and 5, 5, which are adapted respectively to receive the upper and lower folding braces 6 and 7, so as to completely conceal these braces when the costumer sections are collapsed together as illustrated in Figure 1.

The lower brace 7 may be of any conventional form, having a pair of arms 8 and 9 hinged together, as at 10, so as to "break" 50 upwardly to permit the arms to be folded together in collapsing the costumer. The outer extremities of the arms 8 and 9 are respectively received in the grooves 5, and are pivotally connected to the respective standard sections 1 and 2, as by 55

means of the transversely extending pins or pinnacles **11** and **12**, each of which extends transversely through the standard section and the end of the brace arm. Sufficient clearance is afforded between the extreme outer ends of the arms **8** and **9** and the bottom of the grooves **5** to enable the arms to swing upwardly about the pivots **11** and **12**, without binding. The center hinge is preferably of such construction as to prevent the arms from folding downwardly beyond their horizontally aligned position, and this construction may have any suitable form, according to the many well-known types of hinge joints which are available. It will be understood that when the arms **8** and **9** are fully extended, they will remain extended by their own weight, and thereby brace the lower ends of the standard sections **1** and **2** apart, maintaining such braced relation until the hinged joint **10** is broken upwardly by a manual operation, preparatory to collapsing the standard sections together.

Now the upper brace **6** is of special construction which I have designed, and which is provided with an improved locking means for locking the respective arms or links **13** and **14** in a rigidly aligned condition, and without the aid of separate parts such as have heretofore been required. In other words, the brace **6** is of a very simple and efficient form, embodying a minimum number of parts, principally two parts, and is accordingly readily adaptable to inexpensive production, as by casting. Of course, the parts may be made in other manners than by casting, if desired, but I prefer to make each arm **13** and **14** from a single piece of material and having the locking instrumentalities integrally formed therewith.

The arms **13** and **14** are respectively provided with overlapping ears **15** and **16**, as best seen in Figures 2, 3 and 4, which are suitably apertured to receive a pin or rivet **17** which serves to hingedly connect the arms together. One of the arms, in this instance arm **13**, is extended as at **18**, beyond the point of pivotal connection of the two arms, and when the arms are fully extended into alignment, the extension **18** is adapted to lie alongside of the arm **14**. Preferably, the extension **18** is only approximately half the thickness of the section of the arm which lies on the opposite side of the pivot **17**, and the arm **14** is recessed, as at **19**, to a depth approximately equal to the thickness of the extension **18**, so that when the arms are aligned as shown in dotted lines in Figure 3 and in full lines in Figure 4, the uniform continuity of the cross-sectional dimensions of the arms is preserved. This eliminates any material projections or shoulders resulting from the overlapping of the extension **18** with the arm **14**, and provides a substantially smooth-surfaced, bar-like support, upon which garment hangers and the like may be hung and slid along the support as desired, such as when making room for other hangers.

Preferably, the brace **6** "breaks" in a downward direction, as best illustrated in Figure 3, and by reason of such an arrangement, I am enabled to mount the brace **6** on the standard sections **1** and **2** relatively close to the upper extremities thereof, thereby affording ample room between the braces **6** and **7** in which to hang garments which are adapted to be suspended from the brace **6**, and without causing the garment to contact with the floor. The shoulders **20** and **21**, respectively on the arms **13** and **14**, prevent the brace **6** from breaking upwardly, as will be obvious. When fully extended to aligned position, the shoulders **20** and

21 are in abutting engagement, thereby limiting the upward movement of the arms **13** and **14**, beyond the horizontal when unfolding or extending the costumer to the condition shown in Figure 2. The outer extremities of the arms **13** and **14** are respectively pivotally connected to the standard sections **1** and **2**, in much the same manner as the lower brace arms **8** and **9**. Preferably, the outer extremities of the arms **13** and **14** are of special construction for the purpose of positively insuring that the standard sections **1** and **2** will be maintained in a substantially parallel upright relation to each other, thereby further insuring the stability of the costumer when in its extended condition, as will hereinafter become more apparent.

Inasmuch as the brace **6** is adapted to be broken or folded downwardly, means must be provided for locking the arms **13** and **14** in their horizontally aligned position to provide a rigid support for the garment hangers. To this end, I preferably provide the extension **18** of arm **13** with a laterally offstanding lug or projection **22**, which extends towards the other arm **14**, and is adapted to be received in a recess **23** former in the side face of the recess **19**. The lug **22** is relatively short in length so as not to materially interfere with the alignment of the arms **13** and **14** in unfolding or extending the brace. Ordinarily, the lug will readily pass by the lower edge of the arm **14** during the unfolding of the brace, and snap into the recess **23**, although sometimes it may be necessary to apply a slight lateral pressure to the extension **18** to spring the same away from the arm **14** slightly as the extension approaches the end of its movement into the recess **19**, and as the lug **22** approaches the recess **23**. When the lug **22** is received in the recess **23**, the brace parts will assume an interlocked condition, as best seen in Figures 4 and 5. To release or unlock the brace so as to permit it to be folded downwardly, it is merely necessary to apply a slight lateral pressure to the extension **18**, in an amount sufficient to spring the extension **18** laterally away from the adjacent arm **14**, whereby to withdraw the lug **22** from its recess **23**. When the lug **22** is so released, the weight of the arms **13** and **14** will automatically break the hinge downwardly preparatory to enabling the arms to be folded together completely. If the friction at the joints is too great to allow the hinge to break automatically by the weight of the arms when the lug **22** is released from the recess **23**, a slight downward pressure or pull on the brace will start the collapsing of the brace, as will be obvious.

To facilitate the springing of the extension **18** away from the adjacent arm **14**, as in withdrawing the lug **22** from its recess **23** to permit the brace to be collapsed, I preferably provide a fingerpiece, generally designated **24**, on the free extremity of the extension. This fingerpiece, as best shown in Figures 4 and 5, is laterally off-set in the direction of projection of the lug **22**, and the arm **14** is suitably notched, as at **25**, and recessed, as at **26**, to respectively receive the transversely extending portion **27**, and the longitudinally extending portion **28** of the fingerpiece **24**, so that the finger-piece will not project beyond the surface of the arm **14**, and hence the uniform continuity of the brace is fully preserved. It will be noted that the recess **26** is slightly greater in depth than the thickness of the portion **28** of the fingerpiece, whereby to leave a space therebetween, as at **29**, which allows for sufficient lateral springing movement of the ex- 75

tension 18 away from the arm 14 when pressure is applied laterally against the outer face of the fingerpiece, to withdraw the lug 22 from its recess 23, when the arms 13 and 14 are in their aligned and interlocked position.

The outer extremity of each arm 13 and 14 of brace 6, is received in one of the grooves 4 and is pivotally connected with the standard section, as by means of the transversely extending pins 10 or pintles 30 and 31. Each outer extremity is preferably rounded, as best illustrated in Figure 6. In Figure 6, only one arm, arm 14, is illustrated, and it is to be understood that the pivotal connection of arm 13 with standard section 1, and the rounded construction of the outer extremity of arm 13, is identical with the connection and construction of arm 14, as illustrated in this figure. In rounding the outer extremity of each arm, it will be observed that the curvature 20 extends downwardly and inwardly, as indicated by the reference character 32. This affords ample clearance to permit the brace arm to be folded downwardly about its pivotal connection with the standard section, as illustrated in dotted lines in Figure 6, so that when the brace is completely collapsed, the arms will be respectively received in the longitudinal grooves 4, one arm in each groove. The outer upper corner 33 of each arm, from which the curvature 32 extends downwardly, is so positioned that when the arm is unfolded to a horizontal position, the corner 33 will abut against the bottom of the groove 4, or against a suitable bearing plate 34, mounted in the bottom of the groove 4, thereby preventing the arm from unfolding to a position forming an angle with the standard section, greater than a right angle. This will be obvious from Figure 6. When both arms 13 and 14 have been unfolded to their horizontally aligned positions, and interlocked as hereinbefore explained, the standard sections 1 and 2 are both firmly braced against inadvertent tilting towards and from each other, thereby positively insuring that the standard sections will be always upright when the costumer is extended, as illustrated in Figure 2. The rounded extremities of the arms 13 and 14 will be adequate to secure these results, although, if desired, the outer extremities of the arms 8 and 9 of the lower brace 7 may be similarly constructed and arranged. It is, however, not necessary to round the ends of these latter arms, although if they are rounded, the curvature should extend from the outer lower corner of each arm, upwardly and inwardly, inasmuch as the brace 7 is adapted to fold upwardly.

When the costumer is collapsed to bring the standard sections 1 and 2 together, as shown in Figure 1, it is desirable to have some means for securing the sections together so as to maintain such collapsed condition. For this purpose, I have provided on one standard, male members 35, having the form of headed pins, which are respectively mounted adjacent to the upper and lower extremities of the standard. Ordinary wood screws are suitable for the purposes of these headed pins just referred to, and as best seen in Figure 7, the screws are screwed into the standard section at the base of the longitudinal groove, there being preferably one screw in each of the grooves 4 and 5, so that the head of the screw lies slightly beyond the inner face of the standard section and faces towards the opposite standard section. The other standard section is provided with complementary female clamping members 36, having substantially U-shaped form, and

being made of spring metal or equivalent material, whereby to frictionally engage the headed ends of the pins 35. The members 36 are preferably mounted in the respective longitudinal grooves 4 and 5 of the standard section which 5 carries the same, and preferably do not extend beyond the inner face of said section. The outer extremities of the clamping arms 37 of the members 36 are preferably flared, as at 38, to facilitate the entrance of the heads 39 of the pin members 35, therebetween, and when so entered, the heads 39 frictionally interengage with the shoulders 40 so as to prevent the parts from becoming too easily separated. However, by exerting a pull on the standard sections in a direction tending to separate the same, the pin members 35 and the clamping members 36 may be readily pulled apart, allowing the costumer to be conveniently opened up or extended.

Referring now to the foot or base assemblies 1' 20 and 2', and calling attention particularly to Figure 8, in which one of said foot assemblies is illustrated in detail, each foot assembly is composed of a long, transversely extending member 41, the ends of which constitute oppositely disposed feet 42 and 43. A relatively short member 44 forms a third foot 45, and this latter member 44 is disposed at right angles to the member 41. The two members 41 and 44 are preferably crossed, and recessed one within the other 25 at their intersection, as best seen in Figures 2 and 8, and are suitably connected with the lower end of the standard section so that their inner faces are flush with the inner face of the latter. In connecting the foot members to the standard section, I preferably employ fastening means 30 having the form of a threaded bolt 46, having one end permanently mounted in the lower end of the standard section, and having its other end extending below the same so as to pass through the members 41 and 44 at the intersection of the latter. A nut 47 is provided to draw the foot members up tightly against the bottom of the standard section. To brace the feet and to assist in firmly securing the same to the standard 35 sections, I provide a plurality of brace members 48 having substantially triangular-shaped form, there being one brace member for each foot disposed in the corner or crotch formed between each foot and the standard section. The vertical 50 edges of the members 48 are preferably secured to the standard section by dowels 49, while the bottom horizontal edges of the brace members 48 are secured to the feet, as by wood screws 50, which pass through the feet from the underside 55 thereof and upwardly into the brace members 48. By reason of the construction just described, the fastening means for the foot assembly are all completely concealed, while at the same time, they permit the feet to be readily "knocked 60 down" or taken apart, whenever this is desired. The assembly of the feet is exceedingly simple and can be quickly accomplished with a minimum of effort.

It will be observed that the feet 42 and 43 are only half the width of the feet 45. Likewise, the brace members 48 which lie in the corners formed by the feet 42 and 43 and the standard sections, are only half the width of the other brace members 48 which lie in the corners formed by the feet 45 and the standard sections. Consequently, when the costumer is folded to its collapsed condition shown in Figure 1, the foot assembly will be symmetrical and identical on all sides, except 75

ing that at certain of the sides the feet and braces are composed of complemental halves.

The construction and operation of the costumer should be obvious from the foregoing description, taken in conjunction with the drawings, and it will be understood that when the costumer is extended to the condition shown in Figure 2, the upper brace 6 serves as an efficient auxiliary garment support, from which garments may be conveniently suspended, as well as from the usual hooks 3. When the additional supporting function of the brace 6 is not required, the costumer may be collapsed to the condition illustrated in Figure 1, thereby occupying a minimum of space and presenting substantially the same appearance and having the same utility as an ordinary costumer. To collapse the costumer, it is merely necessary to unlock the brace 6, as by applying a slight lateral pressure to the finger-piece 24, while at the same time, urging the arms 13 and 14 downwardly. During the collapsing of the brace 6, the lower brace 7 should also be folded, as by lifting the arms 8 and 9 upwardly with the foot, or otherwise, as desired. When the hinge joints 17 and 19 of braces 6 and 7 respectively, have been "broken", the standard sections 1 and 2 may be readily moved towards each other until their inner faces meet, and during the last portion of the closing movement of the costumer halves, the friction latch members 35 and 33 will become interengaged and firmly hold the sections together until such time as it is desired to extend the costumer to its extended condition.

In Figure 9, there is shown a somewhat modified construction for accomplishing the same results produced by the curved extremities of the upper brace arms as illustrated in Figure 6. It will be understood, of course, that while Figure 9 shows only a fragmentary part of one of the complemental standard sections 1' and a fragmentary part of one of the brace arms 13', it is intended that the parts be duplicated for the other half of the costumer, that is, the other standard section and brace arm. As illustrated in Figure 9, the brace arm 13' is extended, as at 60, beyond the point of pivotal connection of the arm with the standard section 1', the pivotal connection being designated 30' and constituting a pin or pintle transversely extending across the slot or groove 4' in the upper portion of the standard section 1'. This coextensive protuberant part 60 provides a shoulder 61 which is adapted to abut against a shoulder or ledge 62 formed within the slot or groove 4' of the standard section 1'. Instead of making the groove 4' of uniform depth from top to bottom as in the construction illustrated in Figures 2, 6 and 7, the upper portion of the groove 4' may be cut deeper to form the shoulder 62 just referred to. Thus, when the costumer is fully extended, and the upper brace arms are locked in horizontal alignment, the protuberant extension 60 on each of the complemental brace arms will abut and bear firmly against the shoulder 62, there being one shoulder 62 in each of the uppermost grooves of the complemental standard sections, whereby to positively stabilize the costumer and maintain the complemental standard sections in upright parallel relation to each other. Accordingly, the standard sections will be prevented from swaying to one side or the other when opened up or extended as generally illustrated in Figure 2.

When the costumer is collapsed, as generally

illustrated in Figure 1, the brace arms having the construction illustrated in Figure 9 will be received in the grooves and fully concealed, as illustrated in dotted lines in Figure 9. Sufficient clearance, as at 63, is provided to permit the brace arms to freely swing about the pivotal connection such as 30' of Figure 9. As in the form of the invention illustrated in Figures 6 and 7, the same latch means or complemental male and female frictionally engaging members may be provided in association with the modified construction of the brace arms and complemental standard sections shown in Figure 9 for the purpose of holding the costumer in the collapsed condition of Figure 1. One of these latch members, that is, the male member, is designated 35' in Figure 9, and it will be understood that a complemental female member will be provided on the other standard section which cooperates with the section 1'.

While the specific details have been herein shown and described, the invention is not confined thereto, as changes and alterations may be made without departing from the spirit thereof as defined by the appended claims.

Having thus described my invention, what I claim is new and desire to secure by Letters Patent is:

1. A costumer of the class described, comprising a pair of complemental standard sections, and brace means connecting said standard sections together adjacent to the upper extremities of the latter, said brace means including a pair of arms pivotally connected together, the outer extremities of said arms being respectively connected to the standard sections, one of said brace arms being extended beyond the point of its pivotal connection with the other arm so as to extend alongside of the latter when the arms are extended into substantially horizontal alignment with each other, detent means carried by the extended portion of the first mentioned arm and projecting towards the other arm, said other arm having a depression therein for receiving said detent means, and means at the free extremity of the detent carrying extension for disengaging said detent means from said depression, whereby to enable said brace means to be collapsed and permit the standard sections to be brought together.

2. A costumer of the class described, comprising a pair of complemental standard sections, and brace means connecting said standard sections together adjacent to the upper extremities of the latter, said brace means including a pair of arms pivotally connected together, the outer extremities of said arms being respectively connected to the standard sections, one of said brace arms being extended beyond the point of its pivotal connection with the other arm so as to extend alongside of the latter when the arms are extended into substantially horizontal alignment with each other, detent means carried by the extended portion of the first mentioned arm and projecting towards the other arm, said other arm having a depression therein for receiving said detent means, and means for disengaging said detent means from said depression, whereby to enable said brace means to be collapsed and permit the standard sections to be brought together, said last mentioned means comprising a finger-piece laterally offset from the extended arm, the other arm having a recess for receiving said fingerpiece when the arms are substantially aligned as aforesaid, and said fingerpiece being

laterally spaced from the side wall of the recess to permit the same to be pressed towards the side wall to spring the extended arm laterally away from the other arm and release the detent means from engagement with the depression.

5 3. A costumer of the class described, comprising a pair of complemental standard sections each having a base serving to support the same in substantially vertical position, and brace means 10 interconnecting the same, said brace means including a pair of arms pivotally connected together, means for releasably locking said arms in extended horizontal alignment, with the standard sections disposed in spaced vertically 15 parallel position, the outer extremities of said

arms being respectively pivotally connected with the standard sections and having coextensive protuberant projections beyond the points of pivotal connection with the standard sections aforesaid, adapted to limit relative movement 5 of said arms respecting said standard sections, and said standard sections having shoulders provided thereon and constituting abutment means against which the protuberant projections of the brace arms are adapted to bear when the arms 10 are fully extended, whereby to positively maintain the standard sections in vertical parallel relation to each other.

ROLLO BURKETT CURTISS. 15
